UNITED STATES PATENT OFFICE

171,603

HAT

Rose Krieger and Dorothy Langinger,
Hollywood, Calif.

Application October 6, 1953, Serial No. 27,086

Term of patent 7 years

(Cl. D3—13)

To all whom it may concern:

Be it known that we, Rose Krieger and Dorothy Langinger, citizens of the United States, residing at Hollywood, in the county of Los Angeles and State of California, have invented a new, original, and ornamental Design for a Hat, or which the following is a specification, reference being had to the accompanying drawing, forming a part thereof.

Fig. 1 is a top plan view of a hat embodying our new design;

Fig. 2 is a front view thereof; and

Fig. 3 is a side perspective view thereof.

We claim:

The ornamental design for a hat, as shown.

ROSE KRIEGER.

DOROTHY LANGINGER.
